UNITED STATES PATENT OFFICE.

ALBERT PHIL FARROW, OF KNOXVILLE, TENNESSEE.

RADIO-TOY.

Application filed February 26, 1925. Serial No. 11,836.

To all whom it may concern:

Be it known that I, ALBERT P. FARROW, a citizen of the United States, residing at Knoxville, in the county of Knox and State 5 of Tennessee, have invented certain new and useful Improvements in a Radiotoy, of which the following is a specification.

The present invention relates to a toy and aims to provide a device for simulating a 10 radio receiving set and has for its principal object to provide a toy of this nature which will afford amusement and recreation to children whereby they may play and make believe that they are tuning a radio receiving set.

Another important object of the invention is to provide a toy of this nature with a sound creating mechanism which will be operated upon the turning of the imitation tuning 15 dials.

Another important object of the invention is to provide a toy radio receiving head set which when engaged over the ears of a child, will allow him to hear the noise created by 20 the toy.

A still further object of the invention is to provide a toy of this nature which has an exceedingly simple structure that may be manufactured inexpensively and will be 25 strong and durable so as to withstand the usage for which it is designed.

With the above and numerous other objects in view as will appear as the description proceeds, the invention resides in certain 30 novel features of construction and in the combination and arrangement of parts as will be hereinafter more fully described and claimed.

In the drawing

40 Figure 1 is a front elevation of the toy embodying the features of my invention showing a portion of the front of the casing broken away,

Fig. 2 is an end elevation thereof showing 45 the imitation loud speaker removed, and a portion in section, and

Fig. 3 is a detail view showing the toy head set.

50 Referring to the drawing in detail, it will be seen that 1 designates a cabinet which is constructed to simulate closely the cabinet in which is housed a radio receiving set. With this end in view, openings 2 and 3 are provided in the front panel of the cabinet for rotatably receiving dials 4 having operating knobs 5 and hub portions 6.

Plates 7 are attached to the inside face of the front panel of the cabinet over the openings 2 and 3 and are provided with openings for rotatably receiving the hubs 6 of the 60 dials 4. Pegs 8 extend from the end of the hub 2 inwardly of the cabinet and wheels 9 are fixed to the inner ends of the hubs by screws 10 and receive the pegs 8 so that the wheels 9 are mounted for rotation with the 65 hubs 6 of the dials 4.

These wheels 9 are provided at their peripheries with a series of teeth 11. Springs 12 depend from the top of the cabinet one in alinement with the axis of each wheel 9 70 and have on the sides thereof blocks 13. The teeth 11 of the wheels 9 are adapted to engage these blocks so that when the dials are rotated in imitation of the tuning of a radio set, a clicking noise will be made. 75

An imitation switch arm 14 is pivoted on the front panel for engagement with imitation contacts 15. Around one dial it is preferable to write the names of different cities in the United States while about the 80 other dial, there are written the names of foreign cities. At the bottom of the panel, there are provided plug-in openings 15.

A slideway connection 16 is mounted on top of the cabinet for receiving the base of 85 an imitation loud speaker 17. This loud speaker may be easily and quickly attached to or detached from the cabinet.

In Fig. 3 I have shown a toy head set which is to be used with this toy set. This 90 head set consists of an arcuate member 18 for supporting ear pieces 19 at its ends. These ear pieces 19 have a cup-shaped formation and are provided in their side walls with openings 20. A cord 21 extends from 95 one of the ear pieces 19 and terminates in plugs 22 which may be inserted in the plug-in openings 15.

From the above it will be seen that the child may place the head set on his ears and 100 rotate the dials 4 and hear the clicking noise because of the provision of openings 20 in the ear pieces and by the use of his childish imagination play that he is tuning the set and thus obtain considerable enjoyment. 105

The present embodiment of the invention which I have disclosed somewhat in detail attains all the features of advantage which are enumerated as desirable in the statement of the invention and the above description, 110 but it is to be understood that numerous changes in the details of construction, in

the materials, in the proportions, and in the combination and arrangement of parts may be resorted to without departing from the spirit or scope of the invention as herein-
5 after claimed or sacrificing any of its ad-
vantages.

Having thus described my invention, what I claim as new is:—

- 10 1. A toy of the class described including a cabinet having a front panel provided with an opening, a dial rotatable in the opening and having a hub portion, a plate on the inside of the panel over the opening and provided with an opening for rotatably receiving the hub of the dial, a wheel on the inner end of the hub provided with radially extending peripheral teeth, and a spring
- 15

supported on the top of the cabinet extending downwardly to engage the teeth of the wheel whereby when the dial is rotated, a 20 clicking noise will be made.

2. A toy simulating a radio receiving head set including a curved supporting member of resilient material and ear pieces on the ends thereof, each ear piece being 25 cup-shaped in formation and provided in its side wall with a series of openings to allow the sound to pass therethrough so that the wearer of the head set may hear practically the same as though it were not 30 being worn.

In testimony whereof I affix my signature.

ALBERT PHIL FARROW.
